GRINDING MACHINE

Herbert A. Silven, Worcester, Mass., assignor to
 Norton Company, Worcester, Mass., a corpora-
 tion of Massachusetts

Application July 17, 1948, Serial No. 39,362

33 Claims. (Cl. 51—95)

1

The invention relates to grinding machines and more particularly to a hydraulically operated cylindrical type grinding machine.

One object of the invention is to provide a simple and thoroughly practical cylindrical grinding machine. Another object of the invention is to provide an improved hydraulically operated table reciprocating mechanism. Another object of the invention is to provide a hydraulic table reversing mechanism for precisely controlling the reversal of the table movement. Another object is to provide an independent dwell control for producing an adjustable dwell at either or both ends of the table stroke. A further object is to provide a reverse control valve which is arranged to gradually decelerate and accelerate the table movement prior to and after reversal.

Another object is to provide an improved hydraulically operated wheel feeding mechanism whereby a rapid approaching movement is imparted to the grinding wheel after which the grinding wheel is fed at a slower controlled rate during the grinding operation. Another object is to provide a wheel feed mechanism which is arranged to produce a rapid approaching movement of the grinding wheel, then a slower feed for a shoulder grinding operation after which the feed is further reduced to a slower predetermined body feed.

Another object is to provide a wheel feeding mechanism including a piston and cylinder to move the feed screw axially to produce a rapid approaching movement of the grinding wheel and a fluid motor thereafter to rotate the feed screw so as to impart a slow grinding feed to the grinding wheel.

Another object is to provide an improved hydraulic control mechanism whereby the grinding wheel may be fed continuously during a plunge-cut grinding operation or may be fed intermittently at the ends of the reciprocatory stroke of the table during a traverse grinding operation. A further object is to provide a selector valve to facilitate setting up the machine for either a plunge-cut or a traverse grinding operation.

Another object is to provide an automatically actuated mechanism to start the work drive and coolant pump motors when either a plunge-cut or a traverse grinding feed is initiated. Another object is to provide a hydraulically-actuated electrically-controlled mechanism automatically to start both the work drive and the coolant pump motors when either a plunge-cut

2

or a traverse grinding feed is initiated. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

10 One embodiment of the invention has been illustrated in the drawings, in which:

Fig. 1 is a front elevation of the improved cylindrical grinding machine;

15 Fig. 2 is a hydraulic piping diagram showing the hydraulic actuating mechanisms and control valves and piping therefor;

Fig. 3 is a simplified electric wiring diagram showing the electrical controls for the various mechanisms of the machine;

20 Fig. 4 is a fragmentary vertical sectional view, on an enlarged scale, through the control valve apron, showing the control levers in elevation;

Fig. 5 is a fragmentary vertical sectional view, on an enlarged scale, taken approximately on the line 5—5 of Fig. 4, through the reversing lever and control apron;

Fig. 6 is a fragmentary vertical sectional view, on an enlarged scale, taken approximately on the line 6—6 of Fig. 4, through the start-stop lever and control apron;

Fig. 7 is a vertical cross sectional view, on a reduced scale, through the wheel slide and wheel feeding mechanism;

Fig. 8 is a fragmentary sectional view, on an enlarged scale, through the hydraulic rapid grinding wheel positioning mechanism showing the shoulder feed control valve;

Fig. 9 is a vertical sectional view, on an enlarged scale, through the manually operable feed wheel;

Fig. 10 is a fragmentary front elevation of the manually operable feed wheel and associated parts, together with the fluid motor for producing the grinding feed;

45 Fig. 11 is a fragmentary sectional view, on an enlarged scale, through the manually operable table traverse mechanism;

Fig. 12 is a fragmentary hydraulic diagram of the grinding feed mechanism, showing the bypass valve in a by-pass position;

50 Fig. 13 is a horizontal sectional view, on an enlarged scale, through the feed screw clutch; and

55 Fig. 14 is a fragmentary detail view of the

spring-pressed detent for positioning the clutch actuating lever.

An improved hydraulically operated grinding machine has been illustrated in the drawings comprising a base 10 which serves as a support for a longitudinally reciprocable work table 11. The work table 11 is slidably mounted on a flat way 12 and a V-way 13 formed on the upper surface of the base 10.

A transversely movable grinding wheel slide 15 is slidably mounted in the usual manner on a pair of transversely extending flat and V-ways (not shown). The wheel slide 15 serves as a support for a rotatable grinding wheel 16 which is mounted on one end of a rotatable wheel spindle 17. The wheel spindle 17 is preferably driven by means of an electric motor 18 mounted on the upper surface of the wheel slide 15. The motor 18 is provided with a multi V-grooved pulley 19 which is connected by multiple V-belts 20 with a pulley 21 mounted on the other end of the wheel spindle 17.

The slide 15 is arranged to be fed transversely relative to the base 10 by means of a feed screw 22 which is journaled in anti-friction bearings 23 and 24. A half nut 25 depending from the under side of the table 11 meshes with the feed screw 22. It will be readily apparent from the foregoing disclosure that a rotary motion of the feed screw 22 will impart a transverse feeding movement through the nut 25 to the wheel slide 15 to the grinding wheel 16. A manually operable feed wheel 26 is mounted on the front of the machine base to facilitate manual adjustment of the feed screw 22. The driving connections between the hand wheel 26 and the feed screw 22 will be more fully described hereinafter.

The work table 11 is arranged so that it may be transversed longitudinally by means of a manually operable traverse wheel 27 which is operatively connected in the conventional manner to rotate a gear mechanism which meshes with a rack bar 28 (Fig. 11) depending from the underside of the work table 11. The table 11 is also arranged so that it may be reciprocated longitudinally by an automatically controlled hydraulically operated mechanism comprising a cylinder 29 which is mounted on the underside of the table 11. The cylinder 29 contains a pair of spaced pistons 30 and 31. The pistons 30 and 31 are connected by hollow piston rods 32 and 33 respectively with hollow brackets 34 and 35 which are fixedly mounted on opposite ends of the machine base 10.

A fluid pressure system is provided comprising a fluid pump 36 which is driven by an electric motor 37. The fluid pump 36 draws fluid through a pipe 38 from a reservoir 39 formed within the base 10 of the machine. The pump 36 forces fluid under pressure through a pipe 40, through a balanced pressure relief valve 41, and through a pipe 42 to a manually operable start and stop valve 43. The pipe 42 also conveys fluid under pressure to a combined table reverse and dwell control valve 44 and also conveys fluid under pressure to a table reverse control valve 45. In the position of the valves as shown in Figure 2, a fluid actuated by-pass valve 46 is provided so that fluid may be readily by-passed between opposite ends of the cylinder 29 when the parts are in condition for a manual transversing movement of the table 11. As illustrated in Fig. 2, fluid within a cylinder chamber 47 may pass through the hollow piston rod 32, through a hollow bracket 34, through a pipe 48, through a

valve chamber 49, through a pipe 50, through the hollow bracket 35, and through the hollow piston rod 33 into a cylinder chamber 51 formed at the right hand end of the cylinder 29. It will be readily apparent from the foregoing disclosure that in this position of the by-pass valve 46, the table 11 may be readily traversed by manual rotation of the traverse wheel 27 without the necessity of overcoming an unbalanced fluid under pressure within the system.

The start-stop valve 43 is arranged to be manually operated by means of a start-stop lever 52 which is mounted on the outer end of a rock shaft 53 which is in turn rotatably supported in fixed relation with the base 10 of the machine. The rock shaft 53 is provided with a downwardly extending arm 54, the lower end of which is yoke-shaped and provided with studs 55 which engage a collar 56. The collar 56 rides in a groove 57 formed in the right hand end of a valve stem 58. The valve stem 58 is provided with a plurality of valve pistons formed integral therewith forming valve chambers 59, 60, 61, 62 and 63.

In addition to serving as a start-stop valve, the valve 43 also serves as a speed control valve to regulate the speed of travel of the table 11 so that it may be traversed at either a grinding speed or a very slow speed for a grinding wheel truing operation. A needle valve 64 is provided for regulating the grinding speed and a needle valve 65 for regulating the truing speed of the table 11. The operation of the start-stop valve 43 and the needle valves 64 and 65 will be more fully described hereinafter.

The combined reverse and dwell control valve 44 comprises a valve stem 66 which serves as a support for a pair of pilot valves 67 and 68. The central portion of the valve stem 66 located between the pilot valves 67 and 68 serves as a support for a slidably mounted reversing valve 69. The reversing valve 69 is a piston type reversing valve having valve chambers or channels 70 and 71 which function in a manner to be hereinafter described to control the reversal of the table 11. A reversing lever 72 is keyed to a rotatable sleeve 73 which is in turn journaled on a cylindrically shaped supporting member 74 (Fig. 5) which is fixedly supported relative to the base 10. The sleeve 73 is provided with a downwardly extending arm 75 which is connected in the conventional manner by a stud 76 and a shoe 77 which rides in a groove 78 adjustably mounted on the valve stem 66. It will be readily apparent from the foregoing disclosure that when the reversing lever 72 is rocked in either direction, an endwise motion will be imparted to the valve stem 66.

The downwardly extending arm 75 is also connected by means of a stud 79 and a shoe 80 with a spool shaped member 81 which is adjustably mounted on the left hand end of a valve stem 82 of the reversing control valve 45. The valve stem 82 is provided with a plurality of integrally formed valve pistons forming valve chambers 83, 84, 85, 86, 87 and 88 which control the passage of fluid through the valve in a manner to be hereinafter described.

The control lever 72 is arranged so that it may be operated manually to reverse the direction of travel of the table 11 or may be actuated automatically by means of a pair of table dogs 90 and 91 which are adjustably supported by a T slot 92 formed in the front face of the work table 11. The positions of the dogs 90 and 91 determine the length of the reciprocating stroke of the table 11. In order to facilitate a truing operation,

it is desirable to provide means for allowing the table 11 to travel beyond its normal stroke into a truing position. In order to accomplish this result, the control lever 72 is formed in two parts. As illustrated in Fig. 5, the manually operable part of the control lever 72 is pivotally mounted on a horizontally arranged stud 93 which is supported by a second part 72a of the control lever 72. The manually operable part of the control lever 72 is arranged to rock about the stud 93 as a pivot and the combined control lever 72-72a is arranged to rock with the sleeve 73 to shift the valves 44 and 45. The control lever 72 is provided with an inwardly projecting stud 94 which is arranged in the path of the dogs 90 and 91. When it is desired to extend the traverse of the table 11 for a truing operation, the control lever 72 is rocked in a counter-clockwise direction (Fig. 5) so as to rock the pin or stud 94 out of the path of the dog 91 so that the table 11 may traverse a further distance toward the left. The movement of the table 11 toward the left is determined by a third table dog 95 (Fig. 1). The lever 72 may be rocked either manually or automatically. As illustrated in Fig. 5, a tension spring 96 normally holds the control lever 72 with the stud 94 in an operative position.

The pilot valve 67 is formed with a valve chamber 100 which is operatively connected by a passage with a valve chamber 102 formed between the pilot valve 67 and the reversing valve 69. In the position illustrated in Fig. 2, fluid within the pilot valve chamber 100 may exhaust through a needle valve 104 which serves to control the shifting movement of the reversing valve 69 toward the left. Similarly, the pilot valve 68 is provided with a valve chamber 101 (Fig. 2) which is connected by a passage with a valve chamber 103 located between the pilot valve 68 and the reversing valve 69. In the position of the pilot valve as shown in Fig. 2, fluid under pressure from the pipe 42 enters the pilot valve chamber 101 and passes through the passage into the valve chamber 103 to cause the reversing valve 69 to move toward the left at a speed controlled by the needle valve 104. A needle valve 105 is similarly connected so that when the valve parts are shifted in the opposite direction, the needle valve 105 will control fluid exhausting from the valve chamber 103 thereby controlling the rate of movement of the reversing valve 69 toward the right. It will be readily apparent from the foregoing disclosure that the needle valves 104 and 105 serve as dwell control valves independently to control the extent of dwell at each end of the table stroke during a traverse grinding operation.

When it is desired to start a traverse grinding operation, the start-stop lever 52 is rocked in a counter-clockwise direction (Fig. 4) so as to shift the valve stem 58 toward the right (Fig. 2). The movement of the valve stem 58 toward the right is limited by movement of a collar 106 which is fixedly mounted on the left hand end of the valve stem 58 into engagement with a surface 107 of the valve casing 43. When the valve stem 58 is moved to the extreme right hand position, fluid under pressure from the pipe 42 enters a valve chamber 62 and passes outwardly through a pipe 108 which conveys fluid through a pipe 109 into a cylinder chamber 110 to cause a piston 111 to move toward the left (Fig. 2). This movement of the piston 111 serves to render the manually operable traverse mechanism inoperative during hydraulic movement of the table 11. At the same time fluid under pressure passing through a pipe

108 passes through a pipe 112 into a valve chamber 113 in the by-pass valve 46 to shift the valve piston toward the left (Fig. 2) so as to close the by-pass of fluid between the pipes 48 and 50. As shown in Fig. 2, fluid under pressure passes through a pipe 114 to a selector valve 115 to be hereinafter described.

There is a differential piston area between the pilot valves 67 and 68 and the reversing valve 69. When the valve stem 66 is moved by shifting of the table reversing lever 72, fluid under pressure is admitted to either the valve chamber 102 or the valve chamber 103 depending upon the direction of movement of the reversing lever 72. Admission of fluid under pressure into valve chamber 102 or 103 serves to shift the reversing valve 69 to cut off both intake and exhaust of fluid from the table cylinder 29. Just before the reversing valve 69 reaches this position, the reverse control valve 45 is shifted so that the tapered portion of the valve piston 120 decelerates the movement of the table 11. Due to the differential piston areas between pilot valves 67-68 and the reversing valve 69, fluid under pressure in either valve chamber 102 or 103 serves to complete the shifting of the reversing valve 69, the reversing lever 72 and the reverse control valve 45 so as to gradually accelerate and start the table 11 moving in the opposite direction. When the valve moves into the reverse position, a tapered portion of the valve piston 120 serves gradually to accelerate the movement of the table 11 as it starts moving in the reverse direction.

In the position of the valve 44 (Fig. 2), fluid under pressure in the pipe 42 passes through the valve chamber 71 and out through a pipe 116 which connects with the hollow bracket 34 so as to admit fluid under pressure to the cylinder chamber 47 thereby causing the cylinder 29 and the table 11 to move toward the left. During this movement of the table 11, fluid may exhaust from the cylinder chamber 51 through a pipe 117 into the valve chamber 70. Fluid exhausting into the cylinder chamber 70 passes through a pipe 118 into the valve chamber 60 in the valve 43 and passes through a central passage in the valve stem 58 into the valve chamber 61 and passes out through a needle valve 64 which serves to regulate the table speed during a grinding operation. Fluid exhausting through the needle valve 64 passes through a pipe 119 into the valve chamber 83 in the valve 45 and passes through a central aperture within the valve stem into the valve chambers 84 and 85. Due to the tapered end portions of a valve piston 120 located between the valve chambers 84 and 85, the exhaust of fluid through the pipe 119 may be gradually cut off to decelerate the motion of the table 11 before reversal and also gradually to accelerate the table after reversal has taken place. Fluid exhausting through valve chambers 84 and 85 of the valve 45 exhausts through a pipe 121 into the reservoir 39. It will be readily apparent from the foregoing disclosure that the combined reversing and pilot valve 44 serves to control the reversal of fluid under pressure within the hydraulic table cylinder and through throttle valves 104 and 105 independently controls the duration of dwell at each end of the table stroke. The valve 45 serves precisely to regulate fluid exhausting from the table cylinder through the valve 44 and the valve 43 so as to cause a gradual deceleration of the table movement prior to reversal and a gradual acceleration of table movement after reversal has

taken place thereby producing a precise accurate reversal of the table 11.

The needle valve 65 associated with the start-stop valve 43 serves to control fluid exhausting from the table cylinder when the valve 43 is in a truing position to produce a slower predetermined movement of the table 11 during a grinding wheel truing operation. The needle valve 65 is connected into the pipe line 119.

The table 11 continues its movement toward the left until table dog 91 engages stud 94 on the reversing lever 71 and rocks the reversing lever in a counter-clockwise direction to shift the valve stems 66 and 82 toward the right. Movement of the valve stem 66 toward the right serves to cut off fluid pressure from the valve chamber 70 but previous to that time the tapered end portion of the valve piston 120 gradually closes the exhaust port in the valve 45 to gradually decelerate the movement of the table 11. At the same time fluid under pressure from the pipe 42 is admitted to the pilot valve chamber 100, and through the passage into the valve chamber 102 to shift the reversing valve 69 toward the right (Fig. 2). During the movement of the reversing valve toward the right, fluid within the valve chamber 103 exhausts through pilot valve chamber 101 and needle valve 105. The rate of shifting of the reversing valve 69 is determined by the setting of the needle valve 105 so that the period of dwell at the left hand end of the stroke is readily controlled. After the reversing valve 69 has moved through a predetermined distance toward the right, fluid under pressure in the pipe 42 may enter the valve chamber 70 in the valve 44 and pass outwardly through the pipe 117 into the cylinder chamber 51 to cause the table 11 to start its movement toward the right. The starting of the table movement toward the right is controlled in a manner similar to that expressed above. Fluid within the cylinder chamber 47 exhausts through the valve chamber 71, through the pipe 118, through the valve chamber 60 in the start-stop valve 43 and out through the needle valve 64 into the valve chamber 83 of the valve 45 so that the tapered portion of the valve piston 120 will gradually open the exhaust port to gradually increase the exhaust of fluid through the pipe 121 thereby to gradually accelerate the movement of the table 11 in a direction toward the right. It will be readily apparent from the foregoing disclosure that the direction of movement of the table 11 is determined by the actuation of the reversing valve 44 and the reversal of the table 11 is precisely controlled by the simultaneous actuation of the reverse controlling valve 45.

A wheel positioning and feeding mechanism is provided for rapidly causing the grinding wheel 16 to move forwardly to an operative position after which the wheel is advanced at a slow predetermined grinding rate by means of an independent mechanism. The rapid positioning mechanism comprises a slidably mounted sleeve 125 which supports the anti-friction bearings 23 which in turn support the rear end of the feed screw 22. A piston rod 126 is fixedly mounted relative to the sleeve 125 in axial alignment with the feed screw 22. The piston rod 126 is connected to a piston 127 which is slidably mounted within a hydraulic cylinder 128. The cylinder 128 is fixedly mounted relative to the base 10 of the machine.

A feed control valve 129 is mounted directly below the cylinder 128. This valve is a piston type valve comprising a valve stem 130 having valve

75 pistons 131, 132, 133, 134 and 135 formed integrally therewith. As illustrated in Figure 8, fluid under pressure from the pipe 42 enters a valve chamber 136 located between the valve pistons 131 and 132 and passes through a passage 137 into a cylinder chamber 138 to cause the piston 127 to move toward the right (Fig. 8) into a rearward or inoperative position. During this movement of the piston 127, fluid within a cylinder chamber 139 may exhaust through a passage 140 into a valve chamber 141 and out through an exhaust pipe 142.

A compression spring 143 surrounds the valve stem 130 and is interposed between the end cap on the valve 129 and a collar 144 which is fixedly mounted on the valve stem 130. The compression of the spring 143 serves normally to hold the valve stem 130 in its extreme right hand end position (Fig. 8). A solenoid S1 serves when energized to shift the valve stem 130 toward the left (Fig. 8) to cause an approaching movement of the piston 127 and the grinding wheel 16.

In the operation of this wheel positioning mechanism, the piston 127 moves forwardly into engagement with the left hand end of the cylinder (Fig. 8) before the wheel 16 engages the surface of the work to be ground. On the normal movement of the wheel 16 and the piston 127 to an inoperative position, the piston moves only part toward the right hand end of the cylinder 128 except when the parts are moved for a grinding wheel truing operation. On the forward rapid stroke of the piston 127, it is desirable to cushion the rapid approaching movement before the piston 127 engages the end of the cylinder 128. This is preferably accomplished by providing a port 145 which is formed at the end of the passage 137 which is spaced from the left hand end of the cylinder 128. It will be readily apparent that when the piston 127 moves a sufficient distance toward the left, the piston 127 will close the port 145 after which fluid may exhaust from the cylinder chamber 138 through a passage 146 through a needle valve 147 and through a passage 148 into the passage 137, through the valve chamber 136 and out through an exhaust pipe 149. A ball check valve 150 is connected between the passage 146 and 148 so that on the return stroke of the piston 127 to an inoperative or right hand end position (Fig. 8) substantially unrestricted flow of fluid under pressure from passage 137 through passage 148, through ball check valve 150 into the passage 146 thereby bypassing the needle valve 147 so as to start a rapid movement of the piston 127 toward the right. This movement continues until the port 145 is uncovered by the piston 127 after which fluid under pressure passes through the port 145 to complete the inoperative stroke of the piston 127.

When the wheel 16 is moved to an extreme rearward position, it is desirable to provide an automatic cushioning mechanism to retard the rapid rearward motion as the piston 127 approaches the end of its rearward stroke. A spherical end portion 151 is provided on the right hand end of the piston rod 126 which moves into engagement with a spherical end portion 152 formed on the left hand end of a dash pot piston 153. A dash pot cylinder 154 is provided at the other end of the piston 153 which is arranged to exhaust fluid through a passage 155, through a needle valve 156, through a passage 157 which connects with passage 140 so that fluid exhausting from the dash pot cylinder 154 will pass

through the control valve 129 and out through the exhaust pipe 142. The setting of the needle valve 156 will determine the rate of rearward movement of the piston 127 as it approaches the end of its stroke thereby reducing the rapid rearward movement to a slow movement thus preventing undue vibrations in the machine. A ball check valve 158 is connected between the passage 157 and the passage 155 so that when fluid under pressure is passed through passage 140 into cylinder chamber 139 to cause an approaching movement of the piston 127, fluid may also pass through a passage 157, the ball check valve 158, the passage 155 into the dash pot cylinder 154 to return the dash pot piston 153 to its forward position so that it is ready for the next cycle of operation. It will be readily apparent from the foregoing disclosure that the grinding wheel 16 may be rapidly moved to and from an operative position by admitting fluid under pressure into either the cylinder chamber 138 or the cylinder chamber 139 which serves to move the grinding wheel rapidly up to the position where it is about to engage the periphery of the work being ground.

A suitable feeding mechanism is provided for producing a slow precise feeding movement of the grinding wheel during the grinding operation. In the preferred form, a hydraulically operated mechanism is provided so that the feed screw 22 may be rotated either continuously for a plunge-cut grinding operation or intermittently at the ends of the table stroke for a traverse grinding operation. As above described, a manually operable feed wheel 26 is mounted on the front of the machine base 10. The hand wheel 26 is operatively connected to rotate a gear 165 which meshes with a gear 166 which is keyed on the forward end of a rotatable shaft 167. The rear end of the shaft 167 is keyed within the forward end of a rotatable sleeve 168. The forward cylindrical end portion 169 of the feed screw 22 is slidably keyed within the hollow sleeve 168. The forward end of the portion 169 of the feed screw 22 is provided with a spherically shaped stop button 170 which is arranged to move into an engagement with a rounded end of an adjustably mounted stop screw 171 carried by the shaft 167. The rapid positioning movement of the grinding wheel 16 and wheel slide 15 as caused by the piston 127 continues until the stop button 170 engages the end of the stop screw 171 after which the grinding wheel may be fed at a slow rate either by manual rotation of the feed wheel 26 or by a hydraulically operated mechanism to be hereinafter described.

This hydraulic mechanism may comprise a cylinder 172 (Fig. 2) which contains a slidably mounted piston 173. A plurality of rack teeth 174 are cut in the upper surface of the piston 173. The rack teeth 174 mesh with a gear 175 which is rotatably supported on a shaft 176. A gear 164 is keyed on the shaft 17 and meshes with the gear 166 so as to transmit motion of the piston 173 to rotate the shaft 167 and the feed screw 22. When fluid under pressure is passed through a pipe 177 into a cylinder chamber 178 to cause the piston 173 to move toward the right (Fig. 2), a counter-clockwise motion is imparted to the hand wheel 26 and also a rotary motion is imparted to the feed screw 22 to cause an infeeding movement of the wheel slide 15. The infeeding movement continues until a stop abutment 181 carried by the feed wheel 26 moves into engagement with a stop pawl 182 which is pivotally supported by a stud 183 on the front of the

machine base. During the movement of the piston 173 toward the right, fluid within a cylinder chamber 189 may exhaust through a pipe 190.

Similarly, when fluid under pressure is reversed and passed through the pipe 190 into the cylinder chamber 189, the piston 173 will be moved toward the left (Fig. 2) so as to cause a clockwise motion to be transmitted to the hand wheel 26 and also to rotate the feed screw 19 to back off the grinding wheel 16 from the surface being ground.

After a grinding operation has been completed, it is desirable that the piston 173 be moved toward the left Figs. 2, 10 and 12 to start a re-setting movement of the feed wheel 26, before the piston 127 starts its rapid rearward movement to an inoperative position. This is preferably accomplished by connecting the exhaust pipe 142 with a normally closed pressure-actuated valve 160. The valve 160 comprises a valve piston 161 which is normally held in a closed position by means of a compression spring 162. When fluid under pressure is admitted to the cylinder 138 to cause a rearward movement of the piston 127, fluid exhausting from the cylinder chamber 139 and the pipe 142 enters a valve chamber formed at the left hand end of the valve 160. The rapid rearward movement of the piston 127 is delayed until sufficient pressure is built up within the valve 160 to overcome the compression of the spring 162 to move the valve piston 161 toward the right (Fig. 8) so that fluid may exhaust through an exhaust pipe 163 into the reservoir 39. Due to the delayed action of the valve 160, the piston 173 has ample time to start its movement toward the left to cause a rotation of the feed screw 22 to move the grinding wheel 16 out of engagement with the work piece before a rapid rearward movement of the piston 127 is started.

40 A feed control valve 191 is provided for controlling the admission of fluid to and the exhausting of fluid from the cylinder 172. The feed control valve 191 is a piston type control valve comprising a valve stem 192 having valve pistons 193, 194 and 195 formed integrally therewith. The valve 191 is a fluid pressure operated valve which is arranged so that when fluid under pressure is passed through the pipe 42 into the valve chamber 136 of the feed control valve 129 through the passage 145 into the cylinder chamber 138 to move the piston 127 to a rearward or inoperative position, it will also pass through a pipe 149, through the selector valve 115, and through a pipe 196 into an end chamber 197, and the valve stem 192 will be moved into an extreme left hand end position as shown in Fig. 2. During movement of the valve stem 192 into this position, fluid within an end chamber 198 may exhaust through a pipe 199. In the position of the valve 191 (Fig. 2) fluid under pressure from the pipe 42 enters a valve chamber located between the valve pistons 194 and 195 and passes out through the pipe 190a to cause the feed piston 173 to move toward the left into the position illustrated in Fig. 2. At the same time fluid within the cylinder chamber 178 exhausting through the pipe 177 and a pipe 177a enters a valve chamber located between the valve pistons 193 and 194 and passes out through a pipe 200.

70 It is desirable to provide means for relieving fluid pressure in both ends of the feed cylinder 172 to facilitate manual movement of the feed wheel 26 in case it is desired to move the grinding wheel 16 toward or away from the work, or 75 to facilitate movement of the feed pawl 182 out

11

of the path of the abutment 181 without the necessity of overcoming fluid under pressure within either of the cylinder chambers 178 and 189. This is preferably accomplished by providing a bypass valve 205. The bypass valve 205 is a pressure actuated piston type valve comprising a valve stem 206 having a plurality of valve pistons 207, 208 and 209 formed integrally therewith. A compression spring (Fig. 2) contained within the right hand end of the valve 205 serves normally to hold the valve in a feed position (Fig. 2). In this position of the valve 205, pipe 177 is connected through a valve chamber located between the valve pistons 207 and 208 with the pipe 177a and pipe 190 is connected through a valve chamber located between the valve pistons 208 and 209 with a pipe 190a.

A control valve 212 is provided for controlling actuation of the by-pass valve 205. The valve 212 is a manually operable rotary type valve having a control lever 213 which as illustrated in full line position conditions valve 212 for a normal grinding operation. When it is desired to actuate the by-pass valve 205, the lever 213 is shifted into dotted line position 213a so that fluid under pressure passing through the pipe 216 from the feed control valve 191 passes through a passage 215 in the valve 213, through a central aperture in the valve 213 and out through a pipe 217 into an end chamber formed at the right hand end of a valve 260. Fluid under pressure passing through the passage 215 in the valve 212 also passes through a pipe 214 into the valve chamber located between the valve pistons 193 and 194 of the valve 191 and exhausts through a pipe 200. Fluid under pressure entering the end chamber of valve 260 passes through a pipe 210 into an end chamber 211 formed at the left hand end of the by-pass valve 205 to shift the valve stem 206 together with the pistons 207 and 208 toward the right into the position illustrated in Fig. 12. In this position, fluid may readily by-pass from the pipe 171 through the valve chamber located between the pistons 207 and 208 and through the pipe 290 so as to allow free by-pass of fluid between opposite ends of the cylinder 172 thereby allowing unrestrained manual movement of the feed wheel 26.

During a traverse grinding operation, if it is desired to manually control the feed wheel 26 for grinding a portion, such as a shoulder, on the work piece being ground, the lever 213 may be shifted in a clockwise direction to shift the valve 212 so as to admit fluid under pressure through the pipes 217 and 210 to shift the by-pass valve 205 toward the right (Fig. 2) into a by-pass position.

The passage of fluid under pressure through the pipe 217 into the cylinder chamber at the right hand end of the cylinder 260 to move the piston 262 toward the left (Fig. 2) so as to maintain the limit switch LS1 closed and the work drive motor 261 and the coolant drive motor 266 operative during the manual operation of the feed wheel 26. The start-stop lever 52 may then be shifted to shift the start-stop valve 43 to a stop position which serves to stop the movement of the table 11, which also serves to hold the position 127 in its forward operative position. The feed wheel 26 may then be actuated manually to feed the grinding wheel 16 as desired and the table traverse wheel 27 may also be actuated manually to traverse the table 11 if desired. When it is desired to resume the traverse grinding operation, the start-stop lever 52 may be

12

shifted to shift the start-stop valve 43 to a start position to start the traversing movement of the table 11. The lever 213 may then be shifted in a clockwise direction to shift the valve 212 into the position illustrated in Fig. 2 to cut-off fluid from the pipe 210 thereby releasing the compression of the spring to return the by-pass valve 205 to the position illustrated in Fig. 2 so as to resume automatic intermittent feed of the grinding wheel 16 at the ends of the table stroke.

The selector valve 115 above referred to is a rotary type valve having a control lever 218 which is arranged to be positioned as shown in full lines in Fig. 2 to facilitate a plunge-cut 15 grinding operation or in a dotted line position 218a to facilitate a traverse grinding operation. In the full line position, that is plunge-cut, the selector valve 115 connects fluid under pressure so that the feed control valve 191 is controlled 20 by and in timed relation with the feed control valve 129. When the selector valve 115 is positioned for a traverse grinding operation, that is with the lever in position 218a, the control of the feed control valve 191 is shifted so that the 25 start-stop valve 48 will control actuation thereof. In other words, the function of the selector valve 115 is to shift control of the feed control valve 191 from the control valve 129 to the start-stop valve 43 and vice versa depending upon 30 whether a plunge-cut or traverse grinding operation is to be performed.

It is desirable to take up any backlash in the grinding feed mechanism rapidly before the grinding wheel engages the peripheral surface of the work to be ground. This is preferably accomplished by a backlash and rapid approach feed control valve 220. The valve 220 is a shuttle type valve comprising a valve stem 221 having valve pistons 222 and 223 formed integrally therewith. The shuttle valve 220 operates in timed relation with the feed control valve 191. When fluid under pressure is passed through the pipe 196 into the valve chamber 197 to shift the valve stem 192 toward the left, it also passes through a ball check valve 224 into a valve chamber 225 to move the valve stem 221 toward the left into the position illustrated in Fig. 2. During this movement fluid within a valve chamber 226 may exhaust through the pipe 199, through a chamber in the selector valve 115 and exhaust in the same manner as fluid exhausting from the end chamber 198 of the valve 191.

When an infeeding movement is initiated either during a plunge-cut or a traverse grinding operation, both of the valves 191 and 220 are moved toward the right by fluid under pressure. As illustrated in Fig. 2, the selector valve 115 is set for a plunge-cut grinding operation. When the solenoid S1 is energized to shift the control valve 129 to initiate a rapid approaching movement of the grinding wheel 16, fluid passing through the pipe 42 enters the valve chamber 141 and passes through the passage 140 to initiate a rapid approaching movement of the grinding wheel and also passes through the pipe 227, through a chamber in the selector valve 115 and through the pipe 228 and the pipe 199 into the end chamber 198 of the valve 191 and also into the end chamber 226 of the backlash control valve 220 to move both of the valves 191 and 220 toward the right (Fig. 2). The valve stem 192 of the valve 191 moves rapidly into a right hand end position so that fluid under pressure in the pipe 42 will pass through the valve chamber located between the valve pis-

tons 193 and 194 of the valve 191 and pass out through the pipe 177a—177 into the cylinder chamber 178 to initiate a grinding feed. At the same time fluid entering the end chamber 226 of the backlash control valve 220 moves the valve stem 221 toward the right at a rate controlled by a needle valve 229.

During the movement of the valve stem 192 toward the right, a port is uncovered so that fluid may exhaust from the cylinder chamber 189 through the pipe 190 into the valve chamber located between the valve pistons 194 and 195 and pass out through a pipe 230, through a chamber in the selector valve 115 and pass out through a pipe 231 and exhaust through a plunge-cut feed adjusting valve 232 and a pipe 235 into the reservoir 39. In order to take up backlash in the feed mechanism, fluid exhausting from the valve chamber located between the valve pistons 193 and 194 into the pipe 230 may also exhaust through a chamber located between the valve pistons 222 and 223 of the backlash control valve 220 during movement of the valve stem 221 toward the right and exhaust through a needle valve 233 and a pipe 234 into the reservoir 39. The quantity of fluid permitted to exhaust through the backlash control valve is determined by the speed of movement of the valve stem 221 and also the setting of the needle valve 233. By adjustment of the needle valves 229 and 233, sufficient additional fluid may be exhausted from the cylinder chamber 189 of the feed control cylinder 172 during its initial movement rapidly to take up backlash in the parts of the feeding mechanism previously described. After the valve stem 221 has moved a sufficient distance so that the chamber located between the valve pistons 222 and 223 moves past the port at the end of the pipe 230, all fluid exhausting from the cylinder chamber 189 must then pass through the selector valve 115, through the pipe 231 and through the plunge-cut feed adjusting valve 232 which controls the rate of plunge-cut infeeding movement of the grinding wheel. The return stroke of the backlash valve stem 221 from its right hand end to its left hand end position is merely a resetting stroke to position the valve for the start of the next grinding operation. During this return stroke when fluid under pressure is passed through the pipe 196, it may pass substantially unrestricted through the ball check valve 224 into the valve chamber 225 rapidly to move the backlash valve stem 221 into its left hand end position.

When the solenoid S1 is deenergized and spring 143 shifts the valve 129 (Figs. 2 and 8) to cause a rapid rearward movement of the grinding wheel 16, fluid may exhaust from the valve chamber 198 of the feed valve 191, from the valve chamber 226 of the backlash valve 220 and from the chamber 263 of the valve 260 through the pipe 191, the pipe 228, through the selector valve 115 through the pipe 227, through a valve chamber located between the valve pistons 132 and 133 of the feed control valve 129, through a central aperture in the valve stem 130, through a valve chamber formed between the valve pistons 134 and 135 and out through an exhaust pipe 236 into the reservoir 39.

A picker feed control valve 240 is provided to control the infeeding movement of the grinding wheel 16 at the ends of the table stroke when the selector valve lever 218 is moved into position 218a for a traverse grinding operation. The valve 240 is a shuttle type valve comprising a

valve stem 241 having valve pistons 242 and 243 formed integrally therewith. A pipe 244 is arranged to convey fluid under pressure from the pipe 42 through the valve chamber 87 in the reverse control valve 44 into an end chamber 245 in the picker feed control valve 240 to move the valve stem 241 toward the right (Fig. 2). During this movement fluid within an end chamber 246 exhausts through a pipe 247 through a needle valve 248 and a pipe 249 into the valve chamber 88 in the reverse control valve 45 and out through an exhaust pipe 250 into the reservoir 39. The rate of movement of the valve stem 241 may be regulated by the adjustment of the needle valve 248.

With the selector valve 115 set in a traverse grinding position, fluid exhausting from the cylinder chamber 189 passes through the feed control valve 191 in a manner above described through the pipe 230, through the chamber in the selector valve 115 and through a pipe 251 and through a traverse infeed adjusting valve 232, through a pipe 253. During the shifting movement of the reversing valve 44 and the reverse control valve 45, fluid under pressure is admitted to shift the valve stem 241 endwise. During this movement in either direction as controlled by the needle valve 248, a valve chamber 254 momentarily uncovers a port at the end of the pipe 253 to allow a predetermined quantity of fluid to exhaust from the cylinder chamber 189 through the pipe 253, through the valve chamber 254 in the picker feed control valve 240 and out through the exhaust pipe 234. By regulating the picker feed adjusting valve 252 and by regulating the needle valve 248 to control the speed of movement of the valve stem 241, a predetermined infeeding movement of the grinding wheel 16 may be obtained during each reversal of the table at the ends of its stroke.

It is desirable to provide means for automatically stopping and starting the work drive motor and the coolant drive motor so that when the grinding cycle is initiated both of the motors will be set in motion before the grinding wheel is fed into the work. To accomplish this result, a shuttle type valve 260 is provided which contains a pair of disconnected slidably mounted pistons 261 and 262. A chamber 263 is formed between the pistons 261 and 262 so that when fluid under pressure is passed through the pipe 199 it will enter the chamber 263. A slidably mounted plunger 264 engages the left hand end of the piston 261 and is normally urged in a direction toward the right (Fig. 3) by means of a compression spring 265. The plunger 264 is arranged in the path of an actuating roller of a limit switch LS1. When fluid under pressure is admitted to the cylinder chamber 263, the piston 262 being in engagement with the right hand end of the valve 260, the piston 261 will be moved toward the left to transmit a corresponding motion to the plunger 264 so as to close the normally open limit switch LS1 thereby starting both a coolant pump motor 266 and a work drive motor 267 (Fig. 3). Similarly, when fluid under pressure is admitted through a pipe 268 into a chamber 269, both the piston 262 and the piston 261 will be moved toward the left against the compression of the spring 265 so as to close the normally open limit switch LS1. When the limit switch LS1 is closed, a relay CR1 is energized so as to energize a relay MC and thereby close a circuit to start the coolant motor 266 and also

to energize a relay MH to close a second circuit to start the work drive motor 261 (Fig. 4).

A suitable work supporting and rotating mechanism is provided for rotatably supporting a work piece to be ground during a grinding operation. This mechanism may comprise a headstock 270 which is supported on the work table 11. The headstock 270 is provided with a headstock center 271. A footstock 272 having a footstock center 273 is adjustably mounted adjacent to the other end of the table 11. The headstock 270 is preferably driven by the electric motor 267 which is mounted on the upper surface of the headstock 270. The motor 267 is provided with a multiple V-groove pulley 274 which is connected by multiple V-belts 275 with a multiple V-groove pulley 276 which is mounted on the left hand end of a headstock spindle 277. Rotation of the motor 267 will be transmitted to rotate the headstock spindle 277 and the headstock center 271 to rotate a work piece to be ground in the conventional manner.

In grinding certain types of work pieces it is frequently desirable to provide a shoulder grinding feed so that in a plunge-cut grinding operation the wheel may be fed at a shoulder grinding feed to grind a shoulder on the work piece after which the feed is slowed down to a predetermined plunge-cut feed to grind a body or cylindrical portion on the work piece. As illustrated in Figs. 2 and 8, a shoulder grinding feed control valve 280 is fixedly mounted relative to the cylinder 128. The valve 280 is a piston type valve comprising a hollow sleeve type valve member 281. The valve member 281 is provided with a pair of spaced valve pistons 282 and 283 which form a valve chamber 284 therebetween. A compression spring 286 within a valve casing 285 normally serves to hold the valve member 281 in a right hand end position (Fig. 8). A rod 287 is fastened to a bracket 288 which is in turn fixedly mounted on the sleeve 125. The rod 287 is provided with a threaded portion having a nut 289 adjustably mounted thereon. When the sleeve 125 is moved toward the left to cause an approaching movement of the grinding wheel 16, the rapid approaching movement continues until the nut 289 engages the end of the valve member 281 and starts it moving in a direction toward the left (Fig. 8). The right hand end of the rod 287 is supported in a bearing bracket 290. An adjustably mounted dog 291 carried on the right hand end of the rod 287 is arranged in the path of an actuating roller 292 of a limit switch LS2. The limit switch is preferably a normally open limit switch and serves when closed to energize a solenoid valve to be herein-after described.

In the position of the parts (Fig. 8) when the solenoid S1 is energized to shift the valve stem 130 toward the left to initiate a rapid approaching movement of the grinding wheel 16, fluid within the cylinder chamber 138 exhausts through the passage 137, through the valve chamber 136, and out through a port 293, through a pipe 294 into the valve chamber 284 and out through an exhaust pipe 295 into the reservoir 39. The rapid approaching movement of the grinding wheel 16 continues until the nut 289 engages the end of the valve member 281 and moves it toward the left (Fig. 8) so as to cut off the exhaust pipe 295. In this position of the valve 281, fluid exhausting into the valve chamber 284 passes out through a pipe 296 and through a shoulder grinding feed adjusting valve 297 and a pipe 298 into the reser-

voir 39. By adjusting the valve 297, the rate of the shoulder grinding feed may be varied as desired. The shoulder grinding feed is normally more rapid than the cushioning feed at the end of the stroke of the piston 127 as controlled by needle valve 141 so that the shoulder grinding feed will continue until the spherical button 170 of the feed screw shaft 169 moves into engagement with the stop screw 171 after which the body feed of the grinding wheel 16 continues at a rate controlled by the movement of the piston 173 previously described.

During the shoulder grinding feed, it is desirable to retard movement of the feed piston 136 for a plunge-cut grinding operation until the shoulder grinding feed has completed its movement. This is preferably accomplished by means of a normally closed solenoid valve 300. The valve 300 is a piston type valve comprising a valve stem 301 having valve pistons 302 and 303 formed integrally therewith. A tension spring 304 serves normally to hold the valve stem 301 in the position illustrated in Fig. 2. The valve 300 is connected in the pipe line 231 between the selector valve 115 and the plunge-cut feed adjusting valve 232. A valve 305 is positioned in the pipe line 231 to permit preventing any exhaust of fluid through the pipe 231 when a shoulder grinding feed is being employed. With the valve 305 closed, no fluid can exhaust through the pipe 231 from the feed cylinder 173 until the shoulder grinding feed above described has been completed. As the shoulder grinding feed reaches the end of its stroke, dog 291 moving toward the left (Fig. 8) engages roller 292 to close the limit switch LS2 which serves to energize a solenoid S2 to shift the valve stem 301 toward the left (Fig. 2) thus opening the valve 300 so that fluid exhausting from the selector valve 115 may pass through the pipe 231, through a valve chamber located between the valve pistons 302 and 303 of the valve 300 and out through the plunge-cut feed adjusting valve 232 into the reservoir 39 thus starting the plunge-cut feed of the grinding wheel 16 to grind the cylindrical body portion of the work piece. The plunge-cut grinding feed continues as above described until the abutment 181 carried by the feed wheel 182 which serves to stop the infeeding movement of the grinding wheel when the body portion of the work piece has been ground to a predetermined size.

In case it is desired to render the shoulder grinding feed inoperative to obtain a direct plunge-cut grinding feed, the nut 289 is backed-off, that is moved toward the right (Fig. 8) so that it will not engage the valve sleeve 281 during the rapid approaching movement of the piston 127 and the grinding wheel 16. The valve 305 (Fig. 2) is opened to allow fluid exhausting from the selector valve 115 to bypass around the solenoid valve 300, thus rendering the solenoid valve 300 ineffective. In this position of the parts, a plunge-cut grinding operation, with shoulder grinding feed, may be obtained. The grinding wheel 16 rapidly approaches the work piece to be ground by movement of the piston 127 toward the left (Fig. 8). The rapid approaching movement continues until the spherical button engages the stop screw 171 which stops the axial or endwise movement of the feed screw 22 just before the grinding wheel 16 engages the work piece to be ground. The movement of the piston 173 toward the right (Fig. 2), as above described, causes a rotation of the feed screw 22 as gov-

erned by the plunge-cut adjusting valve 232 to produce the desired plunge-cut feeding movement of the wheel slide 15 and the grinding wheel 16.

The electrical control mechanism is illustrated in Fig. 3. A push button switch 310 is provided to energize a relay 311 to start the wheel drive motor 18. A stop switch 312 is provided so that the motor 18 may be stopped when desired. A push button switch 314 is provided for energizing a relay MF to start the motor 37 for driving the hydraulic pressure pump 36. A stop switch 315 is provided to facilitate stopping the hydraulic motor 37 when desired.

A manually operable wheel feed control lever 316 is pivotally supported by a stud 317 on the front of the machine base. The lever 316 is arranged to actuate either a start switch 318 or a stop switch 319 depending upon the direction of movement of the lever 316. A selector switch 320 is provided so that the feed mechanism may be controlled either manually or automatically in case a semi-automatic operation of the machine is desired.

As illustrated in Fig. 3 the selector switch 320 is illustrated in a manually operable position. When it is desired to shift to a semi-automatic control, the actuating knob of the switch 320 is shifted in a counter-clockwise direction which serves to render an electric timer 321 operative. In this position of the parts, when the control lever 316 is rocked in a counter-clockwise direction (Fig. 3), the switch 318 is closed to set the timer 321 in motion. At the same time the solenoid S1 is energized to shift the feed control valve 129 toward the left (Fig. 8) to initiate a rapid approaching movement of the grinding wheel 16. The rapid approaching movement of the wheel continues until the spherical button 370 on the feed screw shaft 169 engages stop screw 171 after which the fluid cylinder 172 and piston 173 serve to produce a plunge-cut feeding movement of the grinding wheel 16 to grind a cylindrical portion on the work piece to a predetermined size. After a predetermined time interval, the electric timer 321 breaks a circuit to deenergize solenoid S1 thus releasing the compression of spring 143 so that the feed control valve 129 returns to the position illustrated in Fig. 8 to initiate a rapid movement of the piston 121 toward the right (Fig. 8) to move the grinding wheel 16 to a rearward or inoperative position. If at any time during the feeding cycle it is desirable to stop the feeding movement, the feed control lever 316 may be rocked in a clockwise direction to open the stop switch 319 thereby resetting the timer 321 and deenergizing the solenoid S1 to return the grinding wheel 16 to an inoperative position.

A manually operable control lever 325 is provided for controlling the work driving motor 267. The lever 325 is pivotally supported by the stud 326 on the front of the machine base. The lever 325 is arranged to actuate a start switch 327 or a stop switch 328 is provided so that the work rotation may be either controlled manually or automatically as desired. As illustrated in Fig. 3, the selector switch 329 is shown in a hand position. In this position of the selector switch 329, when control lever 325 is rocked in a counter-clockwise direction to actuate the start switch 327 closing a circuit to energize the relay switch MH which in turn serves to close a circuit to start the work drive motor 267. When it is desired to stop the work drive motor 267, the work

control lever 325 may be rocked in a clockwise direction to actuate the stop switch 328 thereby breaking the circuit to deenergize the relay switch MH and thereby stopping the motor 267.

5 If it is desired to operate the work drive motor automatically in timed relation with other mechanisms of the machine, the selector switch 329 is shifted to an automatic position. In this position of the selector switch 329, when the pistons 261 or 262 (Fig. 2) are moved to the left to close the limit switch LS1 so as to close a circuit energizing a relay switch CRL which in turn serves to energize a relay switch MC to close a circuit to start the coolant drive motor 266 and also to energize the relay switch MH automatically to start the work drive motor 267. Similarly, when fluid under pressure is cut off from the cylinder 260, the released compression of the spring 265 serves to move the pistons 261 and 262 toward the right (Fig. 2) to allow the normally open limit switch LS1 to open, thereby breaking the circuit to deenergize the relay switch CRL which in turn serves to deenergize the relay switch MC to stop the coolant drive motor 266 and also to deenergize the relay switch MH to break a circuit and thereby stop the work drive motor 267.

25 If it is desired to jog the work, that is to turn the work through a partial turn in setting up the machine or for purposes of inspection of the work piece being ground, the control lever 325 may be rocked in a clockwise direction so that the switch 328 momentarily closes contacts 330 which serves to energize relay switch MH to close a circuit thereby starting the work drive motor 267. The extent of the jogging motion of the motor 267 depends upon how long the control lever 326 holds the switch to close contacts 330.

30 To facilitate setting up the feeding mechanism of the machine when a new wheel is mounted thereon or to set up for a different diameter work piece, it is desirable to provide means for disconnecting the feed wheel 26 from the power actuated mechanism. This is preferably accomplished by means of a clutch mechanism whereby the fluid motor may be disconnected from the feed wheel 26 and feed screw 22. This mechanism comprises a manually operable lever 345 which is rotatably supported in back of the feed wheel 26. The lever 345 is provided with a downwardly extending arm 346 having a cylindrical arrow pointed end portion 347 which is arranged to engage a spring-pressed detent 348 which serves to hold the lever 345 in either a clutched or declutched position. A pivotally mounted bell crank lever 349 is supported by a vertical stud 350. The stud 350 is carried by a bracket 351 mounted on the front of the machine base 10. The bell crank lever 349 is provided with a yoked portion having a pair of opposed screws 352 and 353 which are arranged to engage diametrically opposite sides of the cylindrical arrow pointed projection 347 of the arm 346. The bell crank lever 349 is also provided with a second yoked portion 354 which carries diametrically arranged studs 355 and 356. The studs 355 and 356 are arranged to engage a groove 357 formed in an enlarged sleeve 358 which is fixedly mounted on the forward end of the shaft 176. A clutch member 359 is keyed to the inner end of the shaft 176 (Fig. 13). The clutch member 359 comprises an internal gear which is arranged to mesh with an external gear of the same pitch diameter which is fixedly mounted relative to the gear 175. 35 In the position shown in Fig. 15, the clutch mem-

bers 359 and 360 are engaged so that movement of the piston 173 will be transmitted through the rack 174, the gear 175, the clutch parts 360—359, the shaft 176, the gear 164 to rotate the gear 166 which transmits a rotary feeding movement to the feed screw 22 and also to the feed wheel 26. If it is desired to declutch the piston 173 from the feed screw 22 and the feed wheel 26, the clutch lever 345 is rocked in a clockwise direction (Fig. 10) to rock the bell crank lever in a counter-clockwise direction so as to move the shaft 176 toward the right (Fig. 13) so as to disengage the clutch member 359 from the clutch member 360. In this position of the clutch parts, the feed wheel 26 may be manually rotated to rotate the feed screw and rapidly to position the grinding wheel as desired.

A micrometer adjusting device 385 is provided to facilitate adjustment of the stop abutment 181. A gear 386 is formed integral with the gear 165. A pinion 387, formed integral with the rotatable shaft 388, meshes with the gear 386. A star wheel or gear 389 is keyed to the shaft 388. A spring-pressed detent 390, carried by the hand wheel 26, meshes with or engages the gear 389. A collar 391 is fixedly mounted on the gear 389 and is provided with an annular integral flange 392 which in the position illustrated in Fig. 9 engages a notch 393 formed in the detent 390 to lock the detent 390 in engagement with the star wheel or gear 389 thereby preventing rotation of the pinion 387. A compression spring 394 normally serves to hold the detent 390 in a locked position. A manually operable knob 395 is fixedly keyed on the outer end of the shaft 388. If a rapid adjustment of the stop abutment 181 is desired, in setting-up the machine, the knob 395 (Fig. 9) may be pulled toward the left to move the pinion 387 out of mesh with the gear 386 after which the hand wheel 26 may be rotated to the desired position. When it is desired to adjust the position of the stop abutment 181 relative to the gear 386, the knob 395 is moved toward the right (Fig. 9) against the compression of the spring 394, to unlock the detent 390 and the knob 395 is then rotated to rotate the pinion 387 on the stationary gear 386 thereby readjusting the position of the abutment 181. When the knob 395 is rotated, the teeth of the star wheel or gear 389 ride over the spring-pressed detent 390. Each notch on the star wheel 389 resets the abutment 181 relative to the gear 386 by an amount required to allow an advance of one ten-thousandth of an inch (.0001") of the grinding wheel 16. It will be readily apparent that by a rotary adjustment of the knob 395, the stop abutment 181 may be precisely adjusted to facilitate setting up the machine for grinding work pieces to a predetermined size. This adjustment may also be utilized for resetting the stop abutment 181 to compensate for wheel wear and for resetting after a grinding wheel truing operation.

A manually operable table traverse mechanism is illustrated in Fig. 11. The manually operable traverse wheel 27 is keyed on the outer end of a rotatable shaft 370. A gear 371 is formed integral with the shaft 370 and meshes with a gear 372. The gear 372 is keyed to a rotatable shaft 373. The shaft 373 also supports a gear 374 which is arranged to mesh with a gear 375. The gear 375 is slidably keyed on a rotatable shaft 376. A gear 377 is also keyed on the shaft 376 and meshes with the table rack bar 28. A yoked member 378 is fixedly mounted on a slide rod 379. The yoked member 378 is arranged to engage a

groove 380 formed integral with the gear 375 so that an endwise or axial movement of the rod 379 will throw the gear 375 into or out of mesh with the gear 377. A compression spring 381 serves normally to urge the rod toward the right to maintain the gear 375 in mesh with the gear 377 so that a manual rotation of the hand traverse wheel 27 will be imparted through the gear mechanism above described to cause a longitudinal traversing movement of the table 11. As previously described, when a fluid pressure reciprocation of the table 11 is started, fluid under pressure passes through the pipe 109 into the cylinder chamber 110 to move the piston 111, the rod 379, the yoked member 378 toward the left (Fig. 11) to slide the gear 375 toward the left to throw it out of mesh with the gear 377 so as to render the manually operable traverse wheel 27 inoperative during hydraulic reciprocation of the table 11.

In order to facilitate bleeding the hydraulic system, a manually operable bleeder valve 335 is connected by a pipe 336 with left hand end of the cylinder 29 (Fig. 2). A pipe 337 conveys fluid exhausting through the valve 335 to the reservoir 39. Similarly a manually operable bleeder valve 338 is connected by a pipe 339 with the right hand end of the cylinder 29. A pipe 340 conveys fluid exhausting through the valve 338 to the reservoir 39. The bleeder valves 335 and 338 may be manually opened when desired.

The operation of the improved grinding machine will be readily apparent from the foregoing disclosure. Assuming the mechanisms to have been previously adjusted and the selector valve 115 is positioned with lever 218 in a plunge-cut grinding position as illustrated in Fig. 2, the selector switch 239 positioned for manual control and the selector switch 220 positioned for a manual control (Fig. 3), the machine is started. Push button switch 310 is actuated to start the wheel driving motor 18. The start switch 314 is actuated to start the hydraulic pump motor 37 and the coolant pump motor 266. The work control lever 325 is then rocked in a counter-clockwise direction to actuate the start switch 327 to energize relay MH and thereby start the work drive motor 267. A feeding movement of the grinding wheel 16 may then be obtained by rocking the wheel feed control lever 316 in a counter-clockwise direction to actuate the infeed switch 318 which serves to energize the solenoid S1, as above described, to shift the feed control valve 129 into an infeeding position to cause a rapid approaching feed of the piston 127 which continues until the spherical stop button 170 on the feed screw engages the stop screw 171 after which a slow plunge-cut feed of the wheel is obtained by movement of the piston 173 toward the right (Fig. 2) which transmits a rotary motion to the feed screw. The grinding feed continues until stop abutment 181 carried by the feed wheel 26 engages the stop pawl 182 which stops the infeeding movement of the grinding wheel 16. The wheel feed control lever 316 may then be rocked in a clockwise direction to actuate the stop switch 319 which deenergizes the solenoid S1 thereby releasing the compression of the spring 143 to return the feed control valve 129 into the position illustrated in Fig. 8 to cause the grinding wheel to move to a rearward or inoperative position. When the valve 129 moves to this position, the piston 173 moves toward the left to rotate the feed screw 22 thereby resetting the feed wheel 26 and associated parts into their original position. Due

to the pressure actuated valve 160, the rearward movement of the piston 127 is delayed until sufficient pressure builds up in the pipe line 142 to open the valve to the exhaust line 163. This delayed action allows the screw to be rotated before the rearward axial movement of the screw takes place. If it is desired to operate the machine with an automatic control of the work motor 267, the selector switch 329 is rocked in a counter-clockwise direction to close the automatic side of the switch. In case it is desired to provide an automatic timer control of the wheel feeding movement, the selector switch 320 is similarly rocked in a counter-clockwise direction to close the timer circuit. With the selector switches 329 and 320 in this position, it is merely necessary to actuate the start switches 310 and 314 to start the wheel drive motor 18 and the hydraulic pump drive motor 37. The feed control lever 316 may then be rocked in a counter-clockwise direction to actuate the start switch 318 which, as previously described, causes an automatic plunge-cut feed of the grinding wheel. When fluid under pressure is passed from the selector switch 115 to shift the feed control valve 191 and the backlash control valve 220 toward the right, fluid is also passed through the pipe 199 into the valve chamber 362 automatically to actuate the limit switch LS1 which serves to energize the relay CRI which automatically energizes the relay MH to start the work drive motor 267 and at the same time energizes relay MC to start the coolant drive motor 266. The grinding wheel is moved through a rapid approaching stroke as above described after which the piston 173 rotates the feed screw to cause a slow predetermined plunge-cut feed of the grinding wheel 16. The grinding operation continues for a predetermined time interval as governed by the electric timer 321. After the predetermined time interval, the timer 321 opens a circuit to de-energize the solenoid S1 thereby causing a rearward movement of the grinding wheel 16.

In case it is desired to set up the machine for a traverse grinding operation, the selector switch 320 is set for manual control. The work selector switch 329 may be positioned either for an automatic or a hand control of the work drive motor 267. The push buttons 310 and 314 may then be actuated to start the wheel feed motor 18 and the hydraulic pump motor 37 after which the start-stop lever 52 is shifted in a counter-clockwise direction into the position illustrated in Fig. 1. This movement of the start-stop lever 52 serves to shift the valve stem 58 of the start-stop valve 43 toward the right to start reciprocation of the table 11 and through the other valves previously described to cause an intermittent or picker feed of the grinding wheel at the ends of the table stroke. After the start-stop lever 52 has been shifted into a start position to start reciprocation of the table, the feed control lever 316 is rocked in a counter-clockwise direction to close the start-switch 318 thereby energizing the solenoid S1 to cause the grinding wheel 16 rapidly to approach the work piece. The rapid approaching movement continues as previously described until the spherical button 170 on the feed screw shaft 169 engages the stop screw 171 after which the piston 173 controlled by the picker feed valve 240 produces the intermittent grinding feed at each end of the table stroke during the grinding operation. The infeeding movement at the ends of the table stroke continues until the stop abutment 181 carried by the feed wheel 26 engages the stop pawl 182 after which the start-stop lever 52

may be rocked in a clockwise direction to shift the valve stem 58 of the start-stop valve 43 toward the left into the position illustrated in Fig. 2 thus stopping the table movement. The feed control lever 316 may then be rocked in a clockwise direction to actuate the limit switch 319 thereby deenergizing the solenoid S1 to return the grinding wheel rapidly to an inoperative position previous to which the feed wheel 26 is automatically reset 10 into its initial position.

If a shoulder grinding feed is desired in combination with a plunge-cut grinding operation, the nut 289 is adjusted so that during the rapid approaching movement of the piston 127, the nut 289 will engage the valve sleeve 281 and shift it toward the left (Fig. 8) to change the rapid approaching movement of the grinding wheel 16 to a shoulder grinding feed as governed by the shoulder grinding adjusting valve 297. The shoulder grinding feed continues until the spherical button 170 engages the stop screw 171 and at the same time the dog 291 (Fig. 8) actuates the limit switch SL2 to close a circuit thereby energizing the solenoid S2 to open the valve 300 15 so that fluid may exhaust through the pipe 231 and through the plunge-cut feed for the remainder of the plunge-cut operation. With this shoulder grinding and plunge-cut set-up of the machine, the infeed continues as before until the stop abutment 181 carried by the feed wheel 26 20 engages the stop arm 182.

It will thus be seen that there has been provided by this invention apparatus in which the various objects hereinabove set forth together 25 with many thoroughly practical advantages are successfully achieved. As many possible embodiments may be made of the above invention and as many changes might be made in the embodiment above set forth, it is to be understood that all matter hereinbefore set forth, or shown in the accompanying drawings, is to be interpreted 30 as illustrative and not in a limiting sense.

I claim:

1. In a grinding machine having a longitudinally reciprocable work table, a rotatable grinding wheel, a transversely movable slide therefor, a nut and screw feed mechanism for said slide, means including a fluid motor to rotate said screw, a fluid actuated feed control valve therefor, a piston and cylinder to reciprocate said table, table actuated pilot and reversing valves therefor, a start-stop valve to control the starting and stopping of the table, fluid connections between the start-stop valve and the fluid actuated feed control valve whereby the latter valve is actuated to render the fluid motor operative when the start-stop valve is shifted to a start position, a feed adjusting valve to control the exhaust of fluid from the fluid motor, and a fluid actuated intermittent feed valve actuated in 45 timed relation with the reversing valve to meter a predetermined amount of fluid through said feed adjusting valve from said fluid motor so as to cause a predetermined infeed of the grinding wheel during reversal at each end of the table stroke.

2. In a grinding machine, as claimed in claim 1, in combination with the parts and features therein specified in which the fluid pressure actuated feed control valve is a shuttle-type valve which is operatively connected to control the admission to and exhaust of fluid from the fluid motor, a traverse grinding feed adjusting valve to control the rate of fluid exhausting from said feed control valve so as to control the speed of

said motor and the rate of the traverse grinding feed of the grinding wheel, a second fluid actuated shuttle-type valve which is actuated simultaneously with the first shuttle-type valve, and fluid connections between the shuttle-type valves to meter a predetermined volume of fluid exhausting from the first shuttle-type valve to provide an initial rapid rotation of the feed screw so as to rapidly move the grinding wheel into operative engagement with the work after which the traverse grinding feed adjusting valve controls the rate of infeed at the ends of the table stroke.

3. In a grinding machine having a longitudinally reciprocable work table, a rotatable grinding wheel, a transversely movable slide therefor, a nut and screw feed mechanism for said slide, means including a fluid motor to rotate said screw, a fluid actuated control valve therefor, a piston and cylinder to reciprocate said table, a combined table actuated pilot and reversing valve therefor, a start-stop valve to control the starting and stopping of the table, fluid connections between the start-stop valve and the fluid actuated feed control valve whereby the latter valve is actuated to render the fluid motor operative when the start-stop valve is shifted to a start position, a table-actuated reverse control valve gradually to decelerate the table speed to a predetermined speed prior to reversal, a feed adjusting valve to control the exhaust of fluid from the fluid motor, a fluid actuated metering valve, fluid connections between the reverse control valve and the metering valve whereby the metering valve is actuated by and in timed relation with the reverse control valve, a throttle valve to control the rate of movement of said metering valve, and a chamber in said metering valve which is operative during the shifting movement of the metering valve to meter a predetermined amount of fluid through said feed adjusting valve from said fluid motor so as to cause a predetermined infeed of the grinding wheel during reversal at each end of the table stroke.

4. In a grinding machine having a longitudinally reciprocable table, a rotatable grinding wheel, a transversely movable slide therefor, a nut and screw feed mechanism for said slide, means including a piston and cylinder to move said screw axially to cause a rapid approaching and receding movement of said slide, a manually operable control valve therefor, means including a fluid motor to rotate said screw to produce a predetermined grinding feed, a fluid actuated feed control valve for said motor, a piston and cylinder to reciprocate said table, a combined table actuated pilot and reversing valve therefor including a slidable valve stem having a pair of spaced pilot valve members thereon and a reversing valve member slidably mounted on said stem between the pilot valve members, a start-stop valve to control the starting and stopping of the table, fluid connections between the start-stop valve and the fluid actuated feed control valve whereby the latter valve is actuated to render the fluid motor operative when the start-stop valve is shifted to a start position, a table-actuated reverse control valve gradually to decelerate the movement of said table to a predetermined speed prior to reversal, a feed adjusting valve to control the exhaust of fluid from the fluid motor, a fluid actuated metering valve, fluid connections between the reverse control valve and the metering valve whereby the metering valve is actuated by and in timed relation with the reverse

control valve, a throttle valve to control the rate of movement of the metering valve, and a chamber in said metering valve which is operative during the shifting movement of the metering valve to meter a predetermined amount of fluid through said feed adjusting valve from said fluid motor to cause a predetermined infeed of the grinding wheel during reversal at each end of the table stroke.

5. In a grinding machine having a base, a longitudinally reciprocable work table thereon, a rotatable grinding wheel, a transversely movable slide thereof on said base, a nut and screw mechanism to move said slide, means including a piston and cylinder to move said screw axially to cause a rapid approaching and receding movement of the table, a solenoid-actuated control valve therefor, means including a manually operable hand wheel to rotate said screw, means including an adjustable stop abutment on said hand wheel and a stop pawl on said base to limit the infeeding movement of the grinding wheel, a fluid motor operatively connected to rotate said screw and said hand wheel to impart a grinding feed to said grinding wheel, a fluid actuated feed control valve to start and return said fluid motor, fluid connections between the solenoid actuated feed control valve and the fluid actuated feed control valve whereby the latter valve is actuated to start said fluid motor when a rapid approaching movement of the grinding wheel is initiated, and a feed adjusting valve to regulate fluid exhausting from the fluid motor to control the rate of infeed.

35. 6. In a grinding machine, as claimed in claim 5, in combination with the parts and features therein specified of a fluid pressure actuated by-pass valve for said fluid motor, and a manually operable control valve to admit fluid under pressure to shift said by-pass valve into a by-pass position to connect opposite sides of said fluid motor to facilitate manual adjustment of the stop abutment and feed wheel.

7. In a grinding machine having a base, a longitudinally reciprocable work table thereon, a rotatable grinding wheel, a transversely movable slide thereon on said base, a nut and screw mechanism to move said slide, a piston and cylinder to move said screw axially to cause a rapid approaching and receding movement of the slide, a control valve therefor, a fluid motor operatively connected to rotate said screw to impart a grinding feed to said grinding wheel, a feed control valve to start and return said fluid motor, fluid connections between the solenoid actuated control valve and the fluid actuated feed control valve, and a sequence valve arranged to delay rearward movement of the piston until after the fluid motor has started its return rotation of the feed screw.

8. In a grinding machine having a base, a longitudinally reciprocable work table thereon, a rotatable grinding wheel, a transversely movable slide therefor on said base, a nut and screw mechanism to move said slide, means including a piston and cylinder to move said screw axially to cause a rapid approaching and receding movement of the slide, a solenoid actuated control valve therefor, means including a manually operable hand wheel to rotate said screw, means including an adjustable stop abutment on said hand wheel and a stop pawl on said base to limit the infeeding movement of the grinding wheel, a fluid motor operatively connected to rotate said screw and hand wheel to impart a grinding feed

to said grinding wheel, a fluid actuated feed control valve to start and return said fluid motor, fluid connections between the solenoid actuated control valve and the fluid actuated feed control valve, and a pressure actuated valve arranged to delay rearward movement of the piston until after the fluid motor has started its return rotation of the feed screw.

9. In a grinding machine having a base, a longitudinally reciprocable work table thereon, a rotatable grinding wheel, a transversely movable slide therefor on said base, a nut and screw mechanism to move said slide, means including a piston and cylinder to move said screw axially to cause a rapid approaching and receding movement of the slide, a solenoid-actuated control valve therefor, means including a manually operable hand wheel to rotate said screw, means including an adjustable stop abutment on said hand wheel and a stop pawl on said base to limit the infeeding movement of the grinding wheel, a fluid motor operatively connected to rotate said grinding wheel, a manually operable clutch between the hand wheel and the fluid motor whereby the fluid motor may be disconnected from the hand wheel and screw to facilitate resetting the hand wheel, a fluid actuated feed control valve to start and return said fluid motor, fluid connections between the solenoid actuated control valve and the fluid actuated feed control valve whereby the latter valve is actuated to start said fluid motor when a rapid approaching movement of the grinding wheel is initiated, and a feed adjusting valve to regulate fluid exhausting from the fluid motor to control the rate of infeed.

10. In a grinding machine having a base, a longitudinally reciprocable work table thereon, a rotatable grinding wheel, a transversely movable slide therefor on said base, a nut and screw mechanism for said slide, means including a piston and cylinder to move said screw axially to cause a rapid approaching and receding movement of the slide, a solenoid actuated control valve therefor, a manually operable switch to energize said solenoid so as to initiate an approaching movement of the grinding wheel, an electric timer which is set in motion by said switch to deenergize said solenoid after a predetermined time interval, means including a hand wheel to rotate said screw, means including adjustable stop abutment on said hand wheel and a stop pawl on said base to limit the infeeding movement of the grinding wheel, a fluid motor operatively connected to rotate said screw and said hand wheel to impart a grinding feed to said grinding wheel, a fluid actuated feed control valve to start and return said fluid motor, fluid connections between the solenoid actuated feed control valve and fluid actuated feed control valve whereby the latter valve is actuated to start said fluid motor when a rapid approaching movement of the grinding wheel is initiated, and feed adjusting valve to regulate the fluid exhausting from said fluid motor to control the rate of infeed.

11. In a grinding machine having a longitudinally reciprocable work table, a transversely movable rotatable grinding wheel, a piston and cylinder to reciprocate said table, a reversing valve therefor, a manually operable start-stop valve to control the starting and stopping of table during a traverse grinding operation, a nut and screw feed mechanism for feeding said grinding wheel transversely, a fluid motor to move said screw axially rapidly to move said grinding wheel toward and from said table, a solenoid actuated

control valve therefor, a fluid motor operatively connected to impart a slow rotary motion to said screw to feed the grinding wheel into the work during a traverse grinding operation and/or a

- 5 a plunge-cut grinding operation, a fluid pressure actuated feed control valve to control said fluid motor, a selector valve operatively connected to control said feed control valve, said selector valve being arranged for either a plunge-cut or a traverse grinding operation, fluid connections between the start-stop valve and the selector valve, and fluid connections between the solenoid actuated control valve and the selector valve, said connections being arranged so that when the selector valve is in a plunge-cut position the solenoid actuated valve is connected to control said feed control valve.

10 12. In a grinding machine, as claimed in claim 11, in combination with the parts and features 20 therein specified in which the fluid pressure actuated feed control valve is a shuttle-type valve which is operatively connected to control the admission to and exhaust of fluid from the fluid motor, a plunge-cut feed adjusting valve to control 25 the rate of fluid exhausting from said shuttle valve so as to control the speed of said motor and the rate of the plunge-cut feed of the grinding wheel, a second fluid pressure actuated shuttle-type valve which is actuated simultaneously with 30 the first shuttle-type valve, and fluid connections between the shuttle-type valves to meter a predetermined volume of fluid exhausting from the first shuttle-type valve to provide an initial rapid rotation of the feed screw so as to rapidly move 35 the grinding wheel into operative engagement with the work after which the plunge-cut feed adjusting valve controls the rate of feed.

40 13. In a grinding machine, as claimed in claim 11, in combination with the parts and features 40 therein specified in which the fluid pressure actuated feed control valve is a shuttle-type valve which is operatively connected to control the admission to and exhaust of fluid from the fluid motor, a plunge-cut feed adjusting valve to control 45 the rate of fluid exhausting from said shuttle valve so as to control the speed of said motor and the rate of the plunge-cut feed of the grinding wheel, a second fluid pressure actuated shuttle-type valve which is actuated simultaneously with 50 the first shuttle-type valve, fluid connections between the shuttle-type valves to provide an additional initial exhaust of fluid from the first shuttle-type valve to provide an initial rapid rotation of the feed screw, a throttle valve to control the 55 rate of movement of said second shuttle-type valve to determine the volume of fluid exhausting therethrough thereby to govern the initial rapid rotation of the feed screw.

60 14. In a grinding machine, as claimed in claim 11, in combination with the parts and features 60 therein specified in which the fluid pressure actuated feed control valve is a shuttle-type valve which is operatively connected to control the admission to and exhaust of fluid from the fluid 65 motor, a plunge cut feed adjusting valve to control the rate of fluid exhausting from the feed control valve so as to control the speed of said fluid motor and the rate of the plunge cut feed of the grinding wheel, a second fluid pressure 70 actuated shuttle-type valve which is actuated simultaneously with the first shuttle-type valve, connections between the shuttle-type valves initially to meter a predetermined volume of fluid from the first shuttle-type valve to provide an 75 initial rapid rotation of the feed screw rapidly.

to move the grinding wheel into operative engagement with the work, a throttle valve to control the rate of movement of the second shuttle-type valve, and a second throttle valve to control the rate of fluid exhausting from the second shuttle-type valve, said throttle valves determining the volume of fluid exhausting from the feed control valve and the fluid motor.

15. In a grinding machine, as claimed in claim 11, in combination with the parts and features therein specified of a normally open shoulder grinding control valve to control the exhaust of fluid from the rapid feed cylinder, means actuated by the axial positioning movement of the feed screw to actuate the shoulder grinding control valve to cut off unrestricted exhaust of fluid from said cylinder as the grinding wheel engages a shoulder to be ground, and a shoulder grinding feed adjusting valve thereafter to control the rate of fluid exhausting from said cylinder to produce a predetermined shoulder grinding feed.

16. In a grinding machine, as claimed in claim 11, in combination with the parts and features therein specified of a piston type shoulder grinding feed control valve having a slidably mounted valve member, said valve being arranged normally to facilitate a substantially unrestricted exhaust of fluid from the feed cylinder to cause a rapid approaching movement of the grinding wheel, a rod which is movable axially with the feed screw, an adjustable dog on said rod to engage and shift said valve member to slow down the rapid approaching movement to a predetermined shoulder grinding feed, and a shoulder grinding feed adjusting valve to control the volume of fluid exhausting through said shoulder grinding feed control valve to determine the rate of said shoulder grinding feed.

17. In a grinding machine, as claimed in claim 11, in combination with the parts and features therein specified of a normally closed solenoid valve to render said plunge cut feed adjusting valve inoperative during a shoulder grinding operation, a dog bar movable with the feed screw, an adjustable dog on said bar, and a normally open switch actuated by said dog after a predetermined shoulder grinding feed to energize and open said solenoid valve so as to render the plunge cut feed adjusting valve operative to control a plunge cut feed of the grinding wheel.

18. In a grinding machine, as claimed in claim 11, in combination with the parts and features therein specified of normally open shoulder grinding control valve to control the exhaust of fluid from the rapid feed cylinder, means actuated by the axial positioning movement of the feed screw to actuate the shoulder grinding control valve so as to restrict the exhaust of fluid from said cylinder as the grinding wheel engages a shoulder to be ground, a shoulder grinding feed adjusting valve thereafter to control the rate of fluid exhausting from said cylinder to produce a predetermined shoulder grinding feed, a solenoid valve to render said plunge-cut feed adjusting valve inoperative during a shoulder grinding operation, and means including a limit switch actuated by and in timed relation with the axial movement of the feed screw after a predetermined shoulder grinding operation to actuate said solenoid valve so as to render the plunge-cut feed adjusting valve operative to control a plunge-cut feed of the grinding wheel.

19. In a grinding machine having a longitudinally reciprocable work table, a transversely

movable rotatable grinding wheel, a piston and cylinder to reciprocate said table, a reversing valve therefor, a manually operable start-stop valve to control the starting and stopping of the table during a traverse grinding operation, a nut and screw feed mechanism for feeding said grinding wheel transversely, a fluid motor to move said screw axially rapidly to move said grinding wheel toward and from said table, a solenoid actuated control valve therefor, a second fluid motor operatively connected to impart a slow rotary motion to said screw to feed the grinding wheel into the work during a traverse grinding operation and/or a plunge cut grinding operation, a fluid pressure actuated feed control valve to control said second motor, a selector valve operatively connected to control said shuttle valve, said selector valve being arranged for either a plunge-cut or a traverse grinding operation, fluid connections between the start-stop valve and the selector valve, and fluid connections between the solenoid actuated control valve and the selector valve, said connections being arranged so that when the selector valve is in a traverse grinding position the start-stop valve is arranged to control said shuttle valve.

20. In a grinding machine, as claimed in claim 19, in combination with the parts and features therein specified of means including an electric motor to rotate a work piece to be ground, means including an electric motor driven pump to supply coolant fluid to said grinding wheel and work during a grinding operation, means including a switch to start both of said motors, a piston and cylinder to actuate said switch, and fluid connections between said selector valve and said latter cylinder simultaneously to actuate the feed control valve and the latter piston simultaneously to start both of said electric motors and the fluid motor when the selector valve is in either a plunge-cut or a traverse grinding position.

21. In a grinding machine, as claimed in claim 19, in combination with the parts and features therein specified of a fluid pressure actuated by-pass valve for said second fluid motor, yieldable means normally to maintain said valve in a feeding position, means including an electric work driving motor, means including an electric motor driven coolant pump, means including a switch to start both of said motors, a piston and cylinder to actuate said switch, a manually operable control valve, and fluid connections between said valve and the latter cylinder and by-pass valve whereby actuation of the manually operable control valve serves to admit fluid under pressure to shift the by-pass valve into a by-pass position to facilitate manual operation of the feed wheel and to admit fluid to said cylinder to maintain rotation of the work drive and coolant pump motors, said start-stop valve thereafter serving when shifted to a stop position to stop the table traverse with the grinding wheel in a forward operative position during manual actuation of the feed wheel.

22. In a grinding machine, as claimed in claim 19, in combination with the parts and features therein specified in which the fluid pressure actuated feed control valve is a shuttle-type valve which is operatively connected to control the admission to and exhaust of fluid from the second fluid motor, a traverse grinding feed adjusting valve to control the rate of fluid exhausting from said shuttle valve so as to control the speed of said motor and the rate of the intermittent traverse grinding feed, an intermittent feed fluid

pressure actuated shuttle valve, fluid connections between the latter shuttle valve and the traverse grinding feed adjusting valve, a passage through said latter shuttle valve which is momentarily opened during shifting of the shuttle valve to facilitate an intermittent exhaust of fluid through the feed adjusting valve from the second fluid motor, a throttle valve to control the rate of movement of said latter shuttle valve so as to control the volume of fluid exhausting therethrough, and fluid connections between said reverse control valve and the latter shuttle valve whereby the latter shuttle valve is actuated during reversal at each end of the table stroke to provide a predetermined infeed of the grinding wheel.

23. In a grinding machine, as claimed in claim 19, in combination with the parts and features therein specified in which the fluid pressure actuated feed control valve is a shuttle-type valve which is operatively connected to control the admission to and exhaust of fluid from the second fluid motor, a traverse grinding feed adjusting valve to control fluid exhausting from said second fluid motor through the shuttle-type feed control valve, a second fluid actuated shuttle valve actuated simultaneously with said first shuttle valve to facilitate metering additional fluid exhausting through the shuttle-type feed control valve so as to cause an initial rapid movement of the second fluid motor to take up backlash and rapidly to rotate the feed screw to move the grinding wheel into operative engagement with the work, a fluid actuated shuttle-type intermittent feed valve to facilitate metering fluid exhausting through said feed adjusting valve during the shifting movement of the intermittent feed valve, and connections between said reverse control valve and said intermittent feed valve whereby the intermittent feed valve is actuated during table reversal so as to produce an infeed of the grinding wheel at each end of the table stroke.

24. In a grinding machine having a longitudinally reciprocable table, a piston and cylinder to reciprocate said table, a combined reverse-pilot valve including a slidable valve stem having a pilot valve member thereon and a reversing valve member slidably mounted on said stem to control the admission to and exhaust of fluid from said cylinder, a start-stop valve to control fluid exhausting from said cylinder through said reversing valve to facilitate starting or stopping said table, a throttle valve to control fluid exhausting through the start-stop valve to control the speed of movement of the table, and a reversing control valve to control the exhaust flow of fluid from the throttle valve gradually to decelerate the table speed to a predetermined speed prior to reversal so as to produce a precise reversal of the table.

25. In a grinding machine having a longitudinally reciprocable table, a piston and cylinder to reciprocate said table, a combined reverse-pilot valve including a slidable valve stem having a pair of spaced pilot valve members thereon and a reversing valve slidably mounted on said stem between the pilot valve members to control the admission to and exhaust of fluid from said cylinder, a start-stop valve to control fluid exhausting from said cylinder through said reversing valve to facilitate starting or stopping said table, a throttle valve to control fluid exhausting through the start-stop valve to control the speed of movement of the table, and a reversing control valve to control the exhaust flow of fluid from the

throttle valve gradually to decelerate the table speed to a predetermined speed prior to reversal and to accelerate the table speed after reversal so as to produce a precise and smooth reversal of the table.

5 26. In a grinding machine, as claimed in claim 25, in combination with the parts and features therein specified of means including a manually operable table traverse wheel to traverse the table longitudinally, a fluid pressure operated by-pass valve for said table cylinder, and fluid connections between the by-pass valve and the start-stop valve which are arranged so that fluid is free to by-pass between opposite ends of said cylinder to facilitate manual traversing of said table when the start-stop valve is in a stop position.

20 27. In a grinding machine having a longitudinally reciprocable table, a piston and cylinder to reciprocate said table, a combined reverse-pilot valve to control the admission to and exhaust of fluid from said cylinder, a start-stop valve to control fluid exhausting from said cylinder through said reversing valve to facilitate starting and stopping said table, a pair of independent throttle valves to control fluid exhausting through the start-stop valve to facilitate table movement at either a predetermined grinding or a predetermined truing speed depending upon the position 25 of the start-stop valve, and a reversing control valve including a tapered valve piston to control the exhaust flow of fluid from either of said throttle valves gradually to decelerate the table speed to a predetermined slow speed so as to provide a precise reversal of the table.

30 28. In a grinding machine having a longitudinally reciprocable table, a piston and cylinder to reciprocate said table, a combined reverse-pilot valve to control the admission to and exhaust of fluid from said cylinder, a start-stop valve to control fluid exhausting from said cylinder through said reversing valve to facilitate starting and stopping said table, a pair of independent throttle valves to control fluid exhausting through the start-stop valve to facilitate table movement at either a predetermined grinding or a predetermined truing speed depending upon the position 35 of the start-stop valve, and a reversing control valve including a tapered valve piston to control the exhaust flow of fluid from either of said throttle valves gradually to decelerate the table speed to a predetermined slow speed prior to reversal and gradually to accelerate the table speed after reversal so as to produce a precise and smooth reversal of the table.

40 29. In a grinding machine having a longitudinally reciprocable table, a transversely movable rotatable grinding wheel, a piston and cylinder to reciprocate said table, a combined reversing-pilot valve comprising a valve stem having a pair of spaced pilot valves thereon and a shuttle-type reversing valve slidably mounted on said stem between the pilot valves, a table actuated reversing lever positively to shift said pilot valves and said 45 reversing valve to cut off the exhaust of fluid from the table cylinder and to admit fluid under pressure to a chamber between the reversing valve and one of the pilot valves to shift the reversing valve into a reverse position, an adjustable dwell 50 control valve to retard the shifting movement of the reversing valve to cause a predetermined dwell of the table at the end of its stroke, a manually operable start-stop valve to control fluid exhausting from the table cylinder through said reversing valve to facilitate stopping and starting table

reciprocation, said start-stop valve having a grinding and a truing position, independent throttle valves to control fluid exhausting from the start-stop valve to produce either a predetermined grinding or a predetermined truing speed of the table, and a reversing control valve to control the exhaust flow of fluid from either of said throttle valves gradually to decelerate the table speed to a predetermined speed so as to provide a precise reversal of the table.

30. In a grinding machine having a feed mechanism including a gear, a manually operable feed wheel having a stop abutment to limit rotation of the feed wheel in one direction, an axially-movable pinion normally meshing with said gear, a pinion shaft formed integral with said pinion and rotatably supported on the feed wheel, and a micrometer adjusting device to facilitate a precise adjustment of the stop abutment relative to said gear including a peripherally serrated index plate slidably keyed on said pinion shaft, a spring-pressed detent engageable with the serrations on said index plate, and a manually operable knob fixedly mounted on said pinion shaft, said knob being arranged when rotated to turn the index plate one or more serrations relative to said detent precisely to adjust the stop abutment as desired.

31. In a grinding machine having a feed mechanism including a gear, a manually operable feed wheel having a stop abutment to limit rotation of the feed wheel in one direction, an axially-movable pinion normally meshing with said gear, a pinion shaft formed integral with said pinion and rotatably supported on said feed wheel, and a micrometer adjusting device to facilitate a precise adjustment of the stop abutment relative to said gear including a peripherally serrated index plate slidably keyed on said pinion shaft, a spring pressed detent engageable with the serrations to hold the index plate in an indexed position, and a manually operable knob fixedly mounted on said pinion shaft which is arranged to move the pinion axially out of mesh with said gear to facilitate a rapid adjustment of said abutment, said knob also serving when rotated to turn the index plate one or more serrations relative to the detent precisely to adjust the stop abutment as desired.

32. In a grinding machine having a feed mechanism including a gear, a manually operable feed wheel having a stop abutment to limit rotation of the feed wheel in one direction, an axially-movable pinion normally meshing with said gear, a pinion shaft formed integral with said pinion and rotatably supported on said feed wheel, and

a micrometer adjusting device to facilitate a precise adjustment of the stop abutment relative to said gear including a peripherally serrated index plate slidably keyed on said pinion shaft, a spring pressed detent engageable with the serrations to hold the index plate in an indexed position, a locking device normally to lock said detent in operative engagement with the index plate, and a manually operable knob on said pinion shaft which serves when moved in one direction to move said pinion out of mesh with said gear to facilitate a rapid adjustment of said hand wheel and abutment and when moved in the opposite direction and rotated serves to unlock said detent and to turn the index plate one or more serrations relative to the detent precisely to adjust the stop abutment as desired.

33. In a grinding machine having a feed mechanism including a gear, a manually operable feed wheel having a stop abutment to limit rotation of the feed wheel in one direction, an axially-movable pinion normally meshing with said gear, a pinion shaft formed integral with said pinion and rotatably supported on the feed wheel, and a micrometer adjusting device to facilitate a precise adjustment of the stop abutment relative to said gear including a peripherally serrated index plate slidably keyed on said pinion shaft, a spring pressed detent engageable with the serrations to hold the index plate in an indexed position, a notch on said detent, a locking ring fixedly mounted relative to said index plate, yieldable means normally to hold said ring in engagement with said notch to lock said detent so as to prevent rotation of the index plate and pinion, and a manually operable knob on said pinion shaft which serves when moved in one direction and then rotated to unlock said detent and to turn said index plate one or more serrations precisely to adjust the stop abutment as desired.
